UNITED STATES PATENT OFFICE

142,003

DESIGN FOR A FIGURINE OR SIMILAR ARTICLE

Charlene Champness, Toronto, Ontario, Canada

Application October 5, 1944, Serial No. 115,635

Term of patent 14 years

(Cl. D29—23)

To all whom it may concern:

Be it known that I, Charlene Champness, a citizen of the United States, residing at the city of Toronto, in the county of York, in the Province of Ontario, Canada, have invented a new, original, and ornamental Design for a Figurine or Similar Article, of which the following is the specification, reference being had to the accompanying drawing, forming part thereof.

I claim:

The ornamental design for a figurine or similar article, as shown.

CHARLENE CHAMPNESS.
